UNITED STATES PATENT OFFICE

CHARLES H. YOUNG, OF RIVER POINT, RHODE ISLAND.

RAILWAY-GATE.

SPECIFICATION forming part of Letters Patent No. 230,162, dated July 20, 1880.
Application filed May 13, 1880. (No model.)

Be it known that I, CHARLES H. YOUNG, of River Point, in the county of Kent and State of Rhode Island, have invented certain new and useful Improvements in Railway-Gates; and I do hereby declare that the following specification, taken in connection with the accompanying drawings, forming a part of the same, is a full, clear, and exact description thereof.

My invention relates to a railway-gate which is composed of bars located respectively on each side of the thoroughfare, and which are arranged to be simultaneously raised and lowered, the movement of the said bars being automatically accomplished by a passing train.

My improvements consist in the means employed for securing the movements of the gate, and in mounting the two bars composing the same in such a manner that they are capable of a lateral swinging movement, whereby, should they descend upon a vehicle passing under them, the said vehicle could clear itself and the bars return to their proper positions.

Referring to the drawings, Figure 1 represents, in plan, a section of track supplied with my improved gate. Fig. 2 shows the same in side elevation. Fig. 3 represents, in plan, the mechanism located beneath the road-bed at the crossing. Fig. 4 shows, in elevation, one of the gate-bars and the standard to which it is pivoted; and Figs. 5, 6, and 7 show details of the parts.

A A are the rails located upon the road-bed, which is planked at the crossing in the usual manner. B B are the two bars composing the gate, which bars are arranged one on each side of the thoroughfare crossing the track, and are pivoted to sleeves c c, loosely mounted on standards C C, as shown in Figs. 2 and 4.

As shown in Fig. 4, each gate-bar B is provided near its pivotal point with a hook, b, which engages a portion of the movement of the bar 45 of a vertically-sliding rod, D.

When the bar B is in a horizontal position it bears upon the head of the shoe d, and is supported thereby, as shown in Fig. 4, the hook b being out of engagement; but as the bar rises to its vertical position the tooth b 50 enters the slot in the shoe and fully occupies the same, as shown by broken lines, when

the bar reaches its full height. The movements of the gate-bars are controlled by the vertical movements of the shoes d d, which movements are produced as will hereinafter appear.

The rods D D are journaled in plates secured within the standards E E, so as to move vertically, the said standards protecting the rods 6c from injury by passing vehicles. The lower ends of the rods D D are respectively connected to levers F F, as shown in Figs. 2, 3, and 4, which are pivoted to studs g depending from a base-plate, G. The inner ends of e the levers F F are connected to a crank-arm, H, which is mounted on a rock-shaft, I, secured to proper frame-work under the crossing, as shown in Fig. 2.

In order that the mechanism thus far described shall not be damaged should it become clogged and fail to work, the arm H is loosely mounted on the shaft I, and is connected to said shaft by means of a heavy coiled spring, i, one end of which is secured to the arm H and the other to a collar, h, attached to the shaft by a set-screw, the proper position of the arm H being regulated by a pin, h', passing through a slot in the hub of said arm, as shown in Fig. 3. The shaft I and its immediate connections are located in a pit under the crossing, and are suitably protected from the weather.

As shown in Figs. 2 and 3, an arm, J, is secured to the shaft I near its end, the said arm passing upward to a plane above the road-bed. Secured to the arm J, as shown in Figs. 1 and 2, is a wire rope or chain, K, which extends along one side of the track, and is attached to an adjustable rod, k, which rod is secured to one arm of a bell-crank lever M. This block is located at any desired distance from the crossing—say three or hundred feet—and is secured to the side of the road-bed by bolts m' passing through slots in said block. To one of its ends is hinged a lever, N, having an inclined face, said lever being connected with the other of the bell-crank lever L, as shown in F

As hereinbefore set forth, the movement of the gate-bars, and consequent opening and closing of the thoroughfare, is intended to be accomplished by a passing train. For

preferably the tender, is provided on one side of the vehicles composing the train, with one or more depending arms, each of which is supplied with a roller on its lower end, the said rollers being so adjusted as to come in contact with the inclined face of the train lever N and depress its free end (as the train passes from right to left, Figs. 1 and 2) to the position shown by full lines in Fig. 2. The depression of the lever N causes the inner ends of the levers $F F$ to be rock toward the right, the inner ends of the levers $F F$ to be elevated, the inner ends of the levers $F F$ to be moved downward, and the gate-bars to be brought into a horizontal position by the engagement of the shoes $d d$ with the hooks $b b$. The train having passed the crossing, the opening of the thoroughfare by the elevation of the gate-bars is next in order. This is accomplished by the engagement of the rollers N , located on the same side of the track, but upon the opposite side of the thoroughfare, as shown in Figs. 1 and 2. The lever O is pivoted to a block, P , secured to the sleepers of the ad-bed, and is connected to one arm of a bell-crank lever, Q , also pivoted to said block. The other arm of the lever Q is connected, by rod, q , or a wire rope, to the arm J . Therefore, when the free end of the lever O is depressed to the position shown by dotted lines in Fig. 2 the shaft I is rocked toward the right, and the gate-bars are raised by the upward movement of the rods $D D$ and their s.

Since it is necessary to provide for the opening and closing of the thoroughfare when the train passes in a direction opposite to that desired—that is, from left to right—the other side of the track is supplied with mechanisms which are respectively similar to those already described. A lever, R , Fig. 1, is pivoted to a rod, R' , located a desirable distance from the said lever being connected to a bell-crank lever, S , which, by means of a rope or wire, passing over a pulley, s' , is connected to the arm of a bell-crank lever, T , secured to the shaft I , as shown in Figs. 1 and 3. When the lever R is depressed, therefore, the arm bell-crank lever T is raised, the shaft I is rocked toward the right, and the gate-bars are moved into a horizontal position.

Using the gate-bars and opening the thoroughfare when the train is moving from right, the lever U is provided, the said lever pivoted to a block, U' , secured to the road-bed at any desired distance from the crossing. This lever U is

connected to a bell-crank lever, V , which, by rod, v , or a wire rope, is connected to the arm of the bell-crank lever T , as shown in Fig. 1. When, therefore, the lever U is depressed the shaft I will be rocked to the left and the gate-bars will be moved

into a horizontal position.

not shown in the drawings, it is to

be understood that the arms $J T$, the pulley s' , and the ropes or equivalents $K Q s v$ are covered by planking at the crossing, and the said ropes or equivalents may be protected throughout their entire length. Since the levers $N O R U$ may be located some three or four hundred feet from the crossing, it will be necessary to make some provision for the effects of heat and cold upon the length of the ropes connecting the said levers with the shaft I . In order to compensate for the contraction and expansion of said ropes so that the levers $N O R U$ may at all times produce the requisite motion of the rods $D D$, the levers are attached should be movable on sleepers, and should always be held in a position to keep the ropes taut and the free ends of the levers in an elevated position. In Fig. 2 the block M is shown as provided with means for this purpose. A spring, W , having a bearing against a sleeper or other rigid object, is arranged to press the said block rearward and keep the free end of the lever N in its elevated position, the block sliding on the bolts m' as the temperature increases or decreases.

In order to relieve the ropes connecting the levers $N O R U$ with the shaft I from strain, I prefer to connect their blocks by means of wire ropes or equivalents, as shown at $x x'$, Figs. 1 and 2, to rigid objects at the crossing, the lever-ropes being left a trifle slack. The employment of the ropes $x x'$, however, is not es- sential.

The gate-bars $B B$ may be located at any desired distance above the thoroughfare, but I prefer to place them so that vehicles of ordinary height can pass under them without interference. Since, however, an elevation of the bars sufficient to clear all vehicles might defeat the object of the gates, I have provided them with depending rods hinged to said bars, as shown in Figs. 2 and 4, and have arranged the bars so that should they come in contact with a passing vehicle they would swing in a horizontal plane and allow the vehicle to clear itself. For this purpose the sleeves $c c$, which are loosely mounted on the standards $C C$, are arranged to revolve on said standards and allow the gate-bars to swing in a horizontal plane, the said bars being returned to position by means of weights Y , attached by cords passing over pulleys in the standards $y y$ to arms c' , secured to said sleeves, as shown in Figs. 2, 4, and 7.

If desired, the gate-bars may be balanced, although I have not considered it necessary to show them so constructed.

In the drawings the gate is shown only on one side of the track; but it is to be understood that both sides of the track may be provided with gates which will both be connected with and operated by the rock-shaft J , as described.

Although I have chosen to locate the levers $N O R U$ on the outside of the track and to employ rollers attached to the tender to oper-

ate them, yet I am aware that the said levers and their blocks may be placed on the inside of the track, the rollers be dispensed with, and the said levers be arranged so as to be operated by the flanges upon the car-wheels. If, however, rollers are employed, I prefer that they be adjusted at unequal heights above the rails, in order that the movement of the levers shall be more gradual.

10 The inclined faces of the levers N O R U are in practice much longer and of less inclination than shown in the drawings, and, if desired, the said levers may be balanced. When the levers N O R U are to be depressed by rollers located on the tender, both sides of said tender may be supplied with rollers and arrangements be made for raising those on the side not to be used when the train is running in a certain direction.

20 Although I have shown the rods D D as located exteriorly to the standards C C, yet they may occupy the vertical axes of said standards and the standards E E be dispensed with.

If desired, in place of moving the gate-bars 25 in a vertical plane, they may be arranged to swing in a horizontal plane by substituting rack-bars for the shoes d and employing the proper gears to move the gates horizontally.

In order to give warning to approaching 30 travelers, a gong-bell may be located at the crossing and be connected by suitable devices to the mechanism working the gates.

As far as practicable, all mechanism coming to the weather should be housed.

35 Having described my invention, what I claim, and desire to secure by Letters Patent, is—

1. The combination, with one or more railway-gates located at a road-crossing, and each 40 composed of two swinging bars pivoted on opposite sides of the thoroughfare, of a pivoted lever, N or R, located beside the track and connected with said gate or gates by mechanism substantially as described, whereby 45 by the gate-bars are simultaneously moved to close the thoroughfare by an approaching train, substantially as set forth.

2. The combination, with one or more railway-gates located at a road-crossing, and each 50 composed of two swinging bars pivoted on opposite sides of the thoroughfare, of a pivoted lever, O or U, located beside the track and connected with said gate or gates by mechanism substantially as described, whereby the 55 gate-bars are simultaneously moved to open the thoroughfare by a receding train, substantially as set forth.

3. The combination, with one or more railway-gates located at a road-crossing, and each

composed of two swinging bars pivoted on 60 opposite sides of the thoroughfare, of the pivoted levers N O or R U, located beside the track and connected with said gate or gates by mechanism substantially as described, whereby the gate-bars are simultaneously moved to close and open the thoroughfare by a passing train, substantially as set forth.

4. The combination, with one or more railway-gates located at a road-crossing, and each 70 composed of two swinging bars pivoted on opposite sides of the thoroughfare, of the pivoted levers N O R U, located beside the track and connected with said gate or gates by mechanism substantially as described, whereby the gate-bars are simultaneously moved to close 75 and open the thoroughfare by trains passing in opposite directions, substantially as set forth.

5. The combination, with the gate-bar B b, pivoted so as to move in a vertical plane, of the vertically-movable rod D, provided with a 80 shoe, d, for engaging said bar, substantially as and for the purposes specified.

6. The combination, with the vertically- 85 swinging gate-bar B, pivoted to a sleeve, e, which is journaled on a vertical standard, of a weight, Y, or equivalent, whereby, should the bar be moved in a horizontal plane, it will be returned to its proper position, substantially as set forth.

7. The combination, with a pair of gate- 90 bars arranged to swing in a vertical or horizontal plane, of the vertically-movable rods D, provided with the means described for moving said bars, the levers F, arm H, shaft I, and spring i, the said spring connecting the 95 arm H with the shaft, substantially as and for the purposes specified.

8. The combination, with the sliding block M, P, R', or U', its pivoted lever having an inclined face, its connected bell-crank lever, and a wire rope or equivalent connecting said mechanism with the shaft I of the spring W, whereby the pivoted lever is maintained in its proper elevated position, substantially as set forth.

9. The combination, with the sliding block M, P, R', or U', its pivoted lever having an inclined face, its connected bell-crank lever, and a wire rope or equivalent connecting said mechanism with the shaft I, of a wire rope or equivalent connecting said block with some rigid object, substantially as and for the purposes specified.
